Primary Examiner — Sandra S Snapp*Assistant Examiner* — Ieisha N Price(74) *Attorney, Agent, or Firm* — Dunlap Bennett & Ludwig PLLC(57) **CLAIM**

The ornamental design for a target mount, as shown and described.

DESCRIPTION

FIG. 1 is a top perspective view of a target mount; FIG. 2 is a right side elevation view thereof, the left side elevation view being a mirror image thereof; FIG. 3 is a top plan view thereof; FIG. 4 is a bottom plan view thereof; FIG. 5 is a front elevation view thereof showing the target mount in an alternate position for ease of illustration; FIG. 6 is a rear elevation view thereof showing the target mount in an alternate position for ease of illustration; and, FIG. 7 is a top front perspective view thereof, shown in an assembled configuration.

The broken lines shown in the drawings depict portions of the target mount that form no part of the claimed invention.

1 Claim, 4 Drawing Sheets(56)
